JOSEPH P. MORISSETTE, OF HOLYOKE, MASSACHUSETTS.

THREAD-CUTTING DEVICE FOR SHUTTLES.

1,257,096.

Specification of Letters Patent. Patented Feb. 19, 1918.

Application filed May 29, 1916. Serial No. 100,466.

To all whom it may concern:

Be it known that I, JOSEPH P. MORISSETTE, a subject of the King of England, residing at Holyoke, in the county of Hampden and

5 State of Massachusetts, have invented a new and useful Thread-Cutting Device for Shuttles, of which the following is a specification.

My invention relates to improvements in 10 loom shuttles, and more particularly to cutting devices for such shuttles, or for the filling thread carried thereby; and said invention consists essentially of a member located in the shuttle case behind the eye in 15 such case, and pierced to admit of the passage of a substantially normal filling thread of a given size; a fixed knife or blade placed crosswise of said case, or substantially parallel with said member, and between the latter 20 and said eye; and a tension device located between said member and said blade, and arranged normally to cause the filling thread to travel through a course which is clear of said blade, but adapted, when said thread is 25 suddenly checked, as by the impact of a "lump" on the thread with the aforesaid member, such lump being too large to pass through the opening therein, to yield and allow the thread to be drawn across said 30 blade and so severed, all as hereinafter set forth.

The primary object of my invention is to provide a shuttle with means for cutting the filling thread automatically, when said 35 thread is subjected to an unusual strain, such means affording the necessary tension for the thread and permitting the same to feed freely from the bobbin so long as the loom is working properly and there is no enlargement in the thread which would impair the 40 goods.

As is well known, much damage is frequently caused to the goods by the presence of what are known as "lumps" in the filling thread and which enter into the goods. 45 With this device the thread is severed before such lumps have an opportunity to leave the shuttle. Small knots in the thread may be of no importance, since their presence in the goods does not seriously impair 50

either the texture or appearance thereof, but tangles and especially lumps in the thread are the source of serious damage to the goods, if permitted to get into the same.

A further object is to produce a cutting 55 device, for shuttles, that is simple in construction and operation, consists of few parts which are not liable to get out of order even under the hard usage to which such parts with the shuttle are usually subjected, and is inexpensive, convenient, reliable, and applicable to any ordinary shuttle.

Other objects and advantages will appear in the course of the following description. 65

I attain the objects and secure the advantages of my invention by the means illustrated in the accompanying drawings, in which—

Figure 1 is a top plan of a shuttle case 70 containing a filling carrier or bobbin and equipped with a thread-cutting device which embodies a practical form of my invention; Fig. 2, a cross-section through said case, taken on lines 2—2, looking in the direction of the associated arrow, in Fig. 1; Fig. 3, a cross-section on lines 3—3, looking in the direction of the associated arrow, Fig. 1; Fig. 4, a cross-section on lines 4—4, looking in the direction of the associated 75 arrow, Fig. 1; and, Fig. 5, a top plan in partial section of the new device and the supporting portion therefor of said shuttle case, illustrating the manner in which the thread is severed. 80

Similar numerals of reference indicate corresponding parts throughout the several views.

In the drawings a shuttle case is represented at 1, and a filling carrier at 5 with 90 filling thread 6 wound thereon to form a bobbin. At one end of the case 1 in one side thereof is an eye 7 having therein a bushing 8. These parts and members are all old and well known, both structurally and as to 95 mode of operation. The thread leaves the case 1 by way of the eye bushing 8, and is drawn off of the bobbin as the shuttle is shot back and forth through the shed of the loom. That portion of the thread that is 100

unwound is indicated by the numeral 9, and is the portion most intimately associated with my invention.

A guide and stop member 10, which here is in the form of a transverse partition having a central opening with a bushing 11 therein, is located in the hollow part of the case 1 some little distance back of the eye 7 or of the inner end of the bushing 8. The opening through the bushing 11 has a diameter which adapts said bushing to the particular size of thread used, and this bushing, like the bushing 8, may be changed to accommodate threads of different sizes. While the bushing 11 will permit so much of the thread to pass freely as is suitable for the product of the loom, the passage through said bushing is too small to admit, at least without the bushing offering considerable resistance, any lump or considerable enlargement in the thread. The resistance offered by the bushing 11, assuming that the aforesaid lump or enlargement is able to enter said bushing at all, is sufficient to check the thread 9 or to cause to be imparted to it the pull necessary to sever the same, by the means and in the manner described below.

I utilize as a part of the cutting device the means for putting the ordinary tension on the thread, and such means consists of a support made up of two plates 12 and 13 respectively affixed to opposite side walls of the recess in the case 1 that is between the member 10 and the eye 7 and set off by said member, such recess being indicated by the numeral 14, and two pair of horizontal rods 15 affixed to and extending between said plates, a plate 16 mounted to slide on said rods, and a spring 17 arranged between the plate 12, which is on the same side of said recess in which said eye is located, and said plate 16. Normally the spring 17 maintains the plate 16 against the plate 13, which latter is on the side of the recess 14 that is opposite to the side thereof in which is the eye 7, and the thread 9 is grasped and runs off between said plates and has the necessary tension thereby placed on said thread.

The thread 9 passes through the bushing 11 and between the pressure or tension plates 16 and 13 on the way to the eye 7, and the course of such thread is thus diverted from a straight to a devious path, since said plates are located on one side of the recess 14 and said eye is located in the other side, while said bushing is intermediate of such sides.

Placed in the recess 14 forward of the tension members, or between the latter and the inner end of the bushing 8, is a cutter or blade 18. Thus the member 10, the rods 15, and the blade are all parallel with each other and crosswise of the shuttle case 1. The blade 18 has its cutting edge uppermost, and

such edge inclines downwardly from the eye-provided side of the recess 14 toward the opposite side of said recess, as clearly shown in Fig. 4. At the taller end of the blade 18 there is an angularly-arranged member 19 which is securely attached to the wall of the recess 14 on the eye side. While the thread 9 is in the normal grasp of the tension plates 16 and 13, said thread passes over the adjacent part of the blade 18 to the bushing 8, and clears said blade, because the part of the blade over which said thread then passes is well below the thread.

The complete operation of the device is described as follows: The shuttle having been loaded with the bobbin, the thread 9 from said bobbin is carried in a direction that is generally longitudinal of the case to the member 10 and passed through the bushing 11, then said thread is carried obliquely over in one direction in the recess 14 to the pressure plates 13 and 16 and inserted between them, and finally said thread is carried obliquely across said recess in the other direction, and over the low portion of the blade 18, without touching the latter, to and through the bushing 8 in the eye 7. The shuttle is now ready to be placed in the loom and the thread ready to have the end of the same that protrudes from the eye 7 connected with the work. The thread being thus connected is paid out each time the shuttle is thrown. The thread 9 in passing through the recess 14, from the bushing 11 to the bushing 8, follows the devious or indirect course that leads between the plates 13 and 16, when the latter plate is in normal position—see Fig. 1. The spring 17 is strong enough to maintain the plate 16 in closed position, with the thread 9 between said plate and the plate 13, so long as the thread is paid off in a free and normal manner. The instant, however, that the free delivery of the thread stops, as when the thread becomes tangled upon the bobbin, or the rear end entrance to the bushing 11 encounters a lump, as 20 in Fig. 5, the thread 9 in the recess 14 is straightened and in the act of straightening overcomes the resistance of the spring 17 and forces the sliding plate 16 away from the fixed plate 13. By this act the path of the thread between the bushings 11 and 8 becomes more nearly direct and leads over the higher part of the blade 18, or the part of said blade that is in such path, so that said thread, in straightening out in the manner above explained, passes laterally into contact with said blade and is cut, as represented in Fig. 5. The thread is thus severed in season and at a place to avoid damage to the goods. The spring 17 closes the plate 16 as soon as the thread is cut. The obstructing cause is now removed and the shuttle and thread are again made

ready for the continuance of the weaving operation.

Any unusual pull or strain on the thread is sufficient to cause the thread to be severed with this device, the pull or strain required to produce this result being much less than would be necessary to break the thread by a longitudinal pull, or in other words, to snap or rend asunder the thread.

16 When a shuttle is provided with this attachment or device, the goods woven with the filling thread from such shuttle as the weft thereof are insured against damage from or impairment by tangles, lumps, and other imperfections, of a more or less similar nature, in or on such thread that might otherwise get into said goods, or be the means of damaging them in other ways. This is true because the tangle, lump, or 20 other obstruction on the thread, that is of sufficient size to damage the goods or cause the same to be damaged, is of sufficient size to catch in the bushing 11 and so cause the thread to be automatically severed and the 25 shuttle to run free.

Various changes and alterations in the shape, size, construction, and arrangement of some or all of the parts of the device may be made without departing from my invention, and I do not, therefore, limit myself to the precise details set forth herein and herewith, but seek to embrace such changes and alterations within the scope of the appended claims.

35 In connection with the foregoing, it should be observed that it is conceivable the several parts of the device might be united in such a manner or assembled in such a form that a unitary attachment would be produced for 40 incorporation with the shuttle, instead of attaching the parts separately to the shuttle.

What I claim as my invention, and desire to secure by Letters Patent, is:—

1. The combination, in a device of the 45 class specified, of a shuttle case having an eye, and provided with a thread-guiding member back of such eye, a yielding tension member for said thread, said tension member being arranged normally to divert said thread from an approximately direct course between said first-mentioned member and said eye, and adapted to be actuated to permit said thread to take said approximately direct course when said thread is checked, and a severing implement in the aforesaid approximately direct course of the thread.

2. The combination, in a device of the 50 class specified, with a shuttle case provided with an eye, of a thread guide and stop member in said case, said member being pierced for the passage of thread which is free from enlargements over a predetermined size, a yielding tension member for

said thread, said tension member being arranged normally to divert said thread from an approximately direct course between said first-mentioned member and said eye, and to be actuated to permit said thread to take said approximately direct course, when the thread is checked by said guide and stop member, and a severing implement in the aforesaid approximately direct course of the thread.

3. In a thread-cutting device for shuttles, 75 a shuttle case having an eye, a transverse cutting implement behind said eye, and yielding means arranged behind said implement normally to divert the thread from an approximately direct course leading to 80 said eye, such means being adapted to be actuated by said thread into such course, when the thread is subjected to a sudden pull, to permit the thread to come into contact with said implement.

4. In a thread-cutting device for shuttles, a shuttle case having an eye, a transverse cutting implement behind said eye, yielding means behind said implement, and a perforated thread guide and stop, behind said tension means, to pull on the thread, when an enlargement thereon which is too great to pass freely through said member is encountered by said member, said tension means being then adapted to yield to permit said thread 90 to come into contact with said implement.

5. The combination, in a device of the class specified, with a recessed shuttle having an eye opening through one side adjacent to the outer end thereof, of a blade, 100 yielding tension means, and a perforated guide and stop member arranged in the order named, transversely in the recess in said case, behind said eye, said blade having a cutting edge that inclines downwardly 105 from the end of the blade that is on the side of said recess in which the eye is located, said tension means comprising a spring-pressed plate normally located adjacent to the low part of said blade, and the 110 perforation in said guide and stop member being in offset relation to the normal position of said plate.

6. The combination, in a device of the class specified, with a recessed shuttle case 115 having an eye opening through one side adjacent to one end thereof, of a perforated guide and stop member across the recess in said case, a support in said recess between said member and said eye, a spring-pressed plate mounted on said support and normally contiguous to the side of said recess which is opposite to that in which said eye is located, and a transverse blade in 120 said recess between said support and said eye, said blade having an inclined cutting edge with the low part adjacent to said plate when in normal position, and the per-

foration in said guide and stop member being in offset relation to said plate when normally disposed.

7. The combination, in a device of the 5 class specified, with a shuttle case, of a cutting implement, tension means for the thread, such means being adapted to be operated by an unusual pull on said thread to permit the latter to encounter said im-

plement, and a fixed perforated member ¹⁰ through which said thread extends in order to produce the pull necessary to operate said tension means for the aforesaid purpose.

JOSEPH P. MORISSETTE.
